United States Patent Office

Des. 201,024
Patented May 4, 1965

201,024

PORTABLE BOOKREST

Laurence S. Alexander, Groton, Conn.
(P.O. Box 893, New London, Conn.)

Filed May 26, 1964, Ser. No. 80,165

Term of patent 14 years

(Cl. D33—4)

FIG. 1

FIG. 2

FIG. 3

FIG. 1 is a front elevational view of a portable bookrest embodying my design;

FIG. 2 is a side elevational view thereof, the side not shown being the same as the side shown; and

FIG. 3 is a rear elevational view thereof.

The dominant features of my design reside in the portions shown in full lines.

I claim:

The ornamental design for a portable bookrest, as shown and described.
